UNITED STATES PATENT OFFICE.

FRANKLIN PIERCE PETERSON, OF TULSA, OKLAHOMA.

GAS.

1,094,864.

Specification of Letters Patent. Patented Apr. 28, 1914.

No Drawing.

Application filed January 5, 1914. Serial No. 810,333.

To all whom it may concern:

Be it known that I, FRANKLIN P. PETERSON, a citizen of the United States, residing at Tulsa, in the county of Tulsa and State 5 of Oklahoma, have invented a new and useful Gas, of which the following is a specification.

My invention relates to a composition of matter comprising a new commercial product, gaseous at normal temperatures and atmospheric pressure, but capable of being liquefied and thereafter held in containers 10 in the form of liquefied gas at normal temperatures under pressures practicable for 15 storage and transportation purposes.

Broadly speaking my new product comprises a gas mainly made up of a mixture of any two or more aliphatic hydrocarbons, provided, however, that each of the gases involved 20 in the mixture shall have the characteristics I have outlined above, that is to say that each shall be gaseous under normal temperatures and pressures, and that each shall also have the capability of being confined as 25 a liquid at normal temperatures and at pressures practicable for storing and shipping purposes.

More specifically my new composition of matter essentially consists of a mixture of 30 certain intermediate members of the paraffin or saturated hydrocarbon series; namely, ethene, propane and butane. Under normal conditions of temperature, a mixture of ethane, propane and butane or any two 35 thereof, is gaseous at atmospheric pressure, but may be maintained as a liquid under pressures of between 50 and 500 pounds per square inch, according to the temperature and the relative proportions of the ingredients. 40

An important feature of my invention resides in the fact that my new composition of matter is included among others in the make-up of the so-called "wet" natural 45 gas—by which I mean the gas which exudes or may be pumped from oil wells. As is generally well known, this natural gas although obtainable in vast quantities, in large part has been heretofore, a waste product.

Repeated efforts have been made during the development of the petroleum industry to in 50 some way utilize the valuable illuminating and fuel properties of this gas at points remote from the well from which the gas is obtained.

Wet natural gas contains a considerable

quantity of methane, in addition to a number of other compounds of carbon and hydrogen, the most abundant of which are ethane, propane, butane and pentane and hexane. 60 When this gas is cooled and compressed, certain liquid products separate and a liquid so formed has, in recent years, come into use under the name of "natural gas gasoline" or "casing-head gasoline". This product 65 consists mainly of the higher members of the hydrocarbon family present in wet natural gas, and is a liquid and not a liquefied gas. Except for the recovery of such liquids (which are carried as vapors in the gas) it 70 has heretofore been deemed impossible to make use of any considerable portion of the gas itself, except by piping it for consumption in its natural gaseous state in the immediate neighborhood of the source of its 75 origin.

Repeated attempts have been made to supply liquefied natural gas as a commercial product in a container, but none of these attempts have proved successful for the reason that in the make-up of the gas there is a considerable proportion of methane. This 80 gas in its natural state can be liquefied by cooling it below the critical temperature of methane and applying pressure, and the 85 liquid product so obtained, can be drawn into a container. As soon, however, as the contents of this container become warmed to a temperature above the critical temperature of methane (which is very low) a considerable 90 proportion of them becomes gaseous, and the pressures developed are such as to preclude commercial handling.

My invention relates to a product secured by the elimination from natural gas of 95 those of its constituents, on the one hand, which render its existence in a liquid state at normal temperature impossible, (such as methane), and the elimination of those of its constituents, on the other hand, which are 100 capable of existing as liquids at atmospheric pressures and normal temperatures (such as pentane and the higher paraffins).

More specifically by the separation of the methane and the pentane and hexane together with the other higher members of the hydrocarbon series, from the natural gas, I obtain a product largely made up of ethane, propane and butane, *i. e.* the intermediate members of the paraffin series. 105

The critical temperature of ethane is approximately ninety - three degrees Fahren-

heit, and that of propane approximately two hundred and ten degrees Fahrenheit and that of butane about three hundred and twenty degrees Fahrenheit and each is gaseous under normal conditions of temperature and pressure, and may be liquefied by moderate pressures under normal conditions of temperature. A mixture of two or more of these constituents of natural gas freed from its permanent and gas liquid constituents (such as the higher hydrocarbon compounds on the one hand and methane on the other) possesses all the qualities requisite for a gas to be supplied to the market in liquid form.

15 My new product therefore may be briefly described as mainly a mixture of two or more of those liquefiable constituents of natural gas which can be held as liquids under reasonable and practicable pressures at normal temperatures, and which at normal temperatures and atmospheric pressures are gaseous.

20 A very advantageous process for obtaining my new composition is the one disclosed in my prior Patent No. 1,031,664, July 2, 1912, although it is obvious that other processes might be availed of for the production of this product, without departing from the spirit of my invention.

25 Among the various uses to which my new product may be applied, are its use for machine shop work, for illumination, for supplying and running gas engines, in combination with oxygen for welding, brazing and cutting, in surgery as an anesthetic, it being of course understood that these uses are merely illustrative of the general scope of the usefulness of the product and are by no

means intended to include all the many uses to which it may be put.

I am aware that certain liquid gases are now on the market, such as Pintsch. These gases, however, are radically different from my new composition of matter herein disclosed, first, in that their chemical composition is totally different because they consist mainly of unsaturated hydrocarbons and hydrocyclic compounds, but mainly because they are each of them obtained by an elaborate and expensive process of "cracking" or destructively distilling crude petroleum, whereas my composition may be obtained by an appropriate method of elimination and separation, direct from natural gas.

Having thus described my invention, what I claim as new and desire to secure to Letters Patent of the United States, is:

1. A new composition of matter, consisting of a liquefied mixture of ethane, propane and butane, produced from natural gas and substantially free from the other hydrocarbons.
2. A new composition of matter consisting of a mixture of easily liquefiable constituents of natural gas, substantially freed of methane and of pentane and higher paraffins.

In witness whereof, I hereunto subscribe my name to this specification in the presence of two witnesses.

FRANKLIN PIERCE PETERSON.
